UNITED STATES PATENT OFFICE.

JACOB ZITZERMAN, OF BROOKLYN, NEW YORK.

DESIGN FOR A PHONOGRAPH CABINET.

Application filed December 20, 1923. Serial No. 8,106. Term of patent 14 years.

To all whom it may concern:

Be it known that I, JACOB ZITZERMAN, a citizen of Russia, and a resident of the city of New York, borough of Brooklyn, in the county of Kings and State of New York, United States of America, have invented a new, original, and ornamental Design for a Phonograph Cabinet, of which the following is a specification, reference being had to the accompanying drawings, forming part thereof.

Fig. 2 is a side view thereof.

Fig. 3 is a top plan view.

I claim:

The ornamental design for a phonograph cabinet, as shown.

JACOB ZITZERMAN.
